FIG. 1

FIG. 2

FIG. 1 is a perspective view of a rack for bottles, showing my new design, and

FIG. 2 is a front elevational view thereof.

The sides not shown are the same as those which are illustrated.

The dominant part of the design is shown in FIG. 2 and involves the appearance of the face of the rack obtained by the arrangement of the square transverse joining members giving the corners a beveled effect and the use of spaced parallel longitudinal and vertical members inset in the ends of the square transverse joining members.

I claim:
